UNITED STATES PATENT OFFICE.

GEORGE F. FEISTER, OF MARICOPA, CALIFORNIA.

MEAT SAW.

Application filed November 17, 1925. Serial No. 69,589.

My invention relates to power driven saws especially adapted for use by butchers in cutting the bones occurring in meat.

The principal object of my invention is to provide a simple and easily portable power driven saw to take the place of the usual hand saws commonly used by butchers. A further object is to provide such a saw which can be held and operated by one hand, leaving the other free to hold the work in the same manner as is done when using a hand saw. A still further object is to provide suitable guards for the saw, such guards having the double function of providing a rest to steady the saw and of inclosing it to prevent bone chips from getting upon and into the meat, and to prevent the saw from cutting into or tearing the meat. The guards also protect the operator from injury through contact with the saw.

These and other objects and advantages of the invention will be apparent from the following specification, which should be read with the understanding that the form, proportion, and arrangement of the several parts of the device may be varied, within the limits of the claims hereto appended, without departing from the spirit of the invention as expressed in said claims. It is also to be understood that my invention, although especially adapted for meat saws, may be embodied in saws for other purposes, without material change.

With this in view a preferred embodiment of my invention will now be described fully with reference to the accompanying drawings, wherein:

Fig. 1 is a partly broken front elevation of my meat saw.

Fig. 2 is a central vertical section thereof, the driving motor and cable being shown in elevation.

Fig. 3 is a plan view, the motor and drive shaft being omitted.

In the drawings, the reference numeral 1 designates a circular saw, which is secured, as by means of screws 1', Fig. 1, to a hub 2, and said hub is fixed upon or formed integrally with a shaft 3, Fig. 2, which is rotatably mounted in a journal member 4. This

journal member has a square or rectangular portion 5 lying between two spaced flanges 6, and adapted to slide vertically, without rotating, in a guide way preferably formed as a slot 7 in a plate 8, said guide way or slot extending downwardly from the approximate center of said plate.

The plate 8 forms the back of a guard or housing for the saw 1, the front of said housing being formed by a second plate 9, which is connected with said back plate 8 at its top, as shown at 10, and about half way down its sides, as indicated at 11 in Fig. 1. The lower portions of the plates 8 and 9 are separated by a narrow space 12, Fig. 2, just wide enough to allow the saw 1 to protrude through it when said saw is moved downwardly in the guide slot 7, as shown by dotted lines in Fig. 1. The plates 8 and 9 are inclined with respect to each other, as shown in Fig. 2, their lower portions being closely adjacent to the sides of the saw, and their upper portions being spaced therefrom. A segmental flange or rim 8' may be secured to the lower portion of the plate 8, as shown in Fig. 2.

The journal member 4 is normally retained at the upper limit of its travel in the slot 7 by a U-shaped spring 13, Figs. 1 and 3, one end of which is connected with a pin 14 secured to the top of said journal member, and the other end connected with a pin 15 projecting from the back plate 8. Handle portions 16 are preferably formed upon the two legs of the spring 13, by which it may be grasped conveniently in one hand.

As a preferred means for driving the saw 1, I have shown in Fig. 2 a portable motor 17, connected with the shaft 3 by a flexible drive shaft or cable 18 of well known form. The motor 17 may be supported in any desired manner. For example, I have shown it as provided with a strap or loop 19 by which it may be slung over the arm or shoulder of the operator, or hung upon any other convenient support. A switch is indicated at 20 for controlling the motor.

It is intended that my device will be used, in meat cutting, exactly as the butcher's hand saw is used at present; i. e. the meat

itself will be cut with a knife, down to and around the bone, and my saw then used for cutting through the bone. This is illustrated in Fig. 2, where 21 designates the uncut portion of the meat, 22 is the bone, and 23 indicates a portion of the slice being cut off, and which has already been cut, with a knife, down to the bone 22 and allowed to fold down away from the uncut portion 21.

10 The operator, holding my device in one hand by grasping the handle portions 16 of the spring 13, rests the lower edges of the plates 8 and 9 upon the top of the bone 22 between the uncut portion 21 and the partially cut slice 23, the front plate 9 resting against said uncut portion, and then, by compressing or squeezing together the handles 16, moves the saw 1 downwardly against and through the bone, the housing formed by the plates 8 and 9 remaining in its original position with its bottom edge resting upon the bone. When the saw has passed through the bone, the spring 13 returns it upwardly to its original position in which it is fully inclosed by said housing.

15 By making the plate 9 and the bottom flange 8' of the plate 8 of very thin, stiff metal, such as hard steel, the thickness of the entire lower edge of the device is small enough to allow it to rest upon the bone at the bottom of the knife cut, and the thinness of said plate 9 also enables the saw to cut the bone so close to the plane of the cut surface of the meat that there is no appreciable difference. The inclined relation of the plates 8 and 9 permits ample clearance for the hub 2 and the upper portion of the saw, besides adding to the stiffness of the housing. Moreover, the inclining of the front plate 9 with respect to the saw causes said saw to undercut at a slight angle, so that at the lower side of the bone the cut surface thereof will not protrude beyond the meat by even so much as the thickness of the plate 9.

20 It is to be noted that the housing formed by the plates 8 and 9 has a dual function: it forms the supporting frame and the rest for steadyng the device, and it incloses the saw, wholly or in greater part, thereby protecting the operator from injury, and preventing to a large degree the throwing of bone chips upon or into the meat and the tearing of the meat by coming into contact with the saw.

I claim:

25 1. A sawing device comprising a rotating saw; a housing therefor formed of a pair of spaced plates between which the saw is positioned, the bottom edges of said plates lying closely adjacent to the sides of the saw and being adapted to rest upon the work, and their top edges being more widely spaced from said saw than said bottom edges; a journal member in which said saw is carried; guide means associated with one of said plates and in which said journal member

ber is mounted for movement toward and away from the work; and means for rotating said saw.

2. A sawing device comprising a rotating saw; a housing therefor formed of a pair of plates inclined with respect to each other and between which the saw is positioned, the bottom edges of said plates lying closely adjacent to the sides of the saw and being adapted to rest upon the work, and their top edges being more widely spaced from said saw than said bottom edges and connected together over the top of the saw; a journal member in which said saw is carried; guide means associated with one of said plates and in which said journal member is mounted for movement toward and away from the work; and means for rotating said saw.

3. A sawing device comprising a rotating shaft; a saw secured to one end thereof; a journal member in which said shaft is rotatably mounted; a plate lying substantially parallel to the rear face of said saw and having a slot extending from its approximate center toward its lower edge, said slot forming a guide-way in which said journal member is movably mounted; and a second plate lying adjacent to and completely covering the forward face of said saw, said second plate having a flat unbroken outer surface and being extended around said saw and joined to the first mentioned plate at its top and sides to form, with the first mentioned plate, a housing for said saw, said housing being open at its lower edge to permit the saw to protrude therefrom.

4. A portable sawing device comprising a rotating saw; a housing therefor formed of a pair of spaced plates between which the saw is positioned; a journal member in which said saw is rotatably carried; guide means associated with one of said plates and in which said journal member is movably mounted; and a substantially U-shaped spring for retaining said journal member at one limit of its travel in said guide means, said spring projecting substantially parallel with said plates and forming a handle for the entire device.

5. A portable sawing device comprising a frame provided with a guide way; a journal member movably mounted therein; a saw rotatably carried by said journal member; and a substantially U-shaped spring forming a handle for the device, one end of said spring being connected with said frame and the other end with said journal member for retaining the latter at one limit of its movement in said guide way.

6. A sawing device comprising a plate-like frame member having a slot extending from its central region toward one edge; a journal member movably mounted in said slot; a saw rotatably carried by said journal member and lying adjacent to said plate

member; and a substantially U-shaped spring having one end connected with said plate member and the other end connected with said journal member for retaining the latter at one limit of its movement in said slot.

5. A portable sawing device comprising a frame provided with a guide way; a journal member movably mounted therein: a saw

rotatably carried by said journal member; and a spring for retaining said journal member at one limit of its travel in said guide way, said spring projecting to form a handle for the device.

10. In testimony whereof I have signed my name to this specification.

GEORGE F. FEISTER.
